UNITED STATES PATENT OFFICE.

FLOYD L. FRASER, OF WICHITA, KANSAS.

COMBINED DRUM AND CYMBAL BEATER.

1,042,904.

Specification of Letters Patent. Patented Oct. 29, 1912.

Application filed April 10, 1912. Serial No. 689,756.

To all whom it may concern:

Be it known that I, FLOYD L. FRASER, a citizen of the United States, residing at Wichita, in the county of Sedgwick and State of Kansas, have invented new and useful Improvements in Combined Drum and Cymbal Beaters, of which the following is a specification.

The invention relates to base drum and cymbal beaters, and more particularly to the class of foot-operated beaters.

The primary object of the invention is the provision of a device of this character in which a drum and tympanum may be simultaneously sounded by foot pressure thus allowing freedom of the hands of an operator for performing upon other musical instruments.

Another object of the invention is the provision of a device of this character in which a direct and positive blow may be transmitted simultaneously to the drum and cymbal for effecting a unity of sound therefrom when playing the same, the device being readily and easily attached to and detached from a drum and is under perfect control of the foot of an operator.

Another object of the invention is the provision of a beater of this character in which the drum and cymbal may be simultaneously sounded or the drum or cymbal independently sounded at the option of the operator.

A still further object of the invention is the provision of a device of this character which is simple in construction, thoroughly reliable and efficient in operation and inexpensive in manufacture.

With these and other objects in view the invention consists in the construction, combination and arrangement of parts as will be hereinafter more fully described, illustrated in the accompanying drawings and pointed out in the claims hereunto appended.

In the drawings:—Figure 1 is a perspective view of a drum and cymbal beater constructed in accordance with the invention. Fig. 2 is a vertical, longitudinal, sectional view through the device, the same being shown applied to the rim portion of a drum. Fig. 3 is a fragmentary plan view of the beater stick or staff showing the cymbal beater by full lines at right angles thereto and by dotted lines in parallel relation to the same.

Similar reference characters indicate cor-

responding parts throughout the several views in the drawings.

Referring to the drawings by numerals the device comprises a flat, elongated base 5 forming a stationary jaw 6 at one end thereof and from the same rises a hollow tubular standard or post 7 the same being formed at its upper end with a fork 8 terminating in spaced parallel bearing ears 9 between which is swingingly supported the beater rod supporter of the beater mechanism presently described.

Mounted above the base 5 is a movable jaw 10 which is connected to the post 7 by means of a pivot 11 and cooperates with the stationary jaw 6 for clamping engagement, with the rim or hoop 11' of a drum said jaws being held in clamping relation to each other by means of a set screw 12 loosely passing through the jaw 10 and engaged in the jaw 6, thus securely holding the said jaws in clamping position on the hoop of the drum. Mounted in the bearing ears 9 of the fork is a spindle or pivot 13 on which is loosely engaged the sleeve 14 of the drum beating staff holder which is formed with a crank 15 terminating in a barrel or sleeve 16 at right angles to the said sleeve 14 and in which is adjustably secured a drum beating staff or stick 17 having formed at its outer end a resilient beater head 18 designed as a striker for hitting the drum head for the beating thereof. Formed on the barrel or sleeve 16 is an arm 19 in which is loosely connected an inverted V-shaped wire bail 20, the in-turned ends 21 of which loosely engage in extension ear 22 formed on a foot pedal 23 the same being further provided with ear extensions 24 engaging a pivot 25 mounted in a cross head 26 connected with the base 5 in a manner presently described. The cross-head 26 is formed with a central boss 27 in which is engaged the outer end of a connecting rod 28 the inner end of which is inserted through a suitable opening in the base 5 into a recess 29 formed in the under face thereof and is engaged in a bracket 30 stationarily mounted in the recess 29 for rigidly connecting the said rod 28 to the base. The pedal 23 is formed with an upturned toe abutting flange 31 which prevents the toe portion of the shoe on the foot of the operator from coming in contact with the up-right or post 7 when the pedal 23 is being operated. Arranged within the hollow upright or post 7 is a coiled retractile

spring 32 the same being fixed at one end to a stud 33 while its opposite end is connected with a link 34 detachably engaging the hook 35 fixed in and projecting from the sleeve 14, the spring 32 being designed to tension the beater staff or stick 17 when the same is moved toward the head of the drum and also to retract it when pressure upon the pedal 23 has been released therefrom.

- 10 Adjustably connected to the beater staff or stick 17 is a clip 36 having a bifurcated end 37 in which is swingingly connected by means of a pivot 38 an arch arm 39 the same carrying at its outer end a tapping ball 40 adapted to strike the tympanum or cymbal for the sounding thereof when the drum is being tapped. Fixed to the clip 36 is a leaf spring 41 which frictionally engages the inner pivot end of the arm 39 so that the said 15 arm may be swung in parallel relation to the staff or stick 17 when the tympanum or cymbal is not to be sounded. Normally the arm 39 is held in alinement with the clip 36 whereby the tapping ball 40 will strike the 20 tympanum or cymbal for the sounding thereof on the beating of the drum.

The link 34 is formed of two parts and connected with the same is an adjusted member 42 which is designed to regulate the 25 tension of the spring 32 so as to effect the proper throw of the shaft 17 on its retracting movement.

From the foregoing description, taken in connection with the accompanying drawings, it is thought that the construction and 30 operation of the invention will be clearly understood, and therefore, a more extended explanation is omitted.

What is claimed is:—

- 40 1. A device of the class described comprising a base, a hollow post rising from said base, a pivoted jaw on the post and cooperative with the said base for clamping engagement with the hoop of a drum, a fork 45 formed on said post, a rocking member pivoted in said fork, a beater stick adjustably connected in said member and having a resilient striker head, a foot pedal pivotally connected with said base, connection between the pedal and said member and resilient means fixed in said post and connected with the said member for tensioning the same.

- 50 2. A device of the class described comprising a base, a hollow post rising from said base, a pivoted jaw on the post and cooperative with the said base for clamping

engagement with the hoop of a drum, a fork formed on said post, a rocking member pivoted in said fork, a beater stick adjustably connected in said member and having a resilient striker head, a foot pedal pivotally connected with said base, connection between the pedal and said member, resilient means fixed in said post and connected with the said member for tensioning the same, a cymbal beater adjustably connected with said stick and adapted to be swung from operative to inoperative position.

3. A device of the class described comprising a base, a hollow post rising from said base, a pivoted jaw on the post and cooperative with the said base for clamping engagement with the hoop of a drum, a fork formed on said post, a rocking member pivoted in said fork, a beater stick adjustably connected in said member and having a resilient striker head, a foot pedal pivotally connected with said base, connection between the pedal and said member, resilient means fixed in said post and connected with the said member for tensioning the same, a cymbal beater adjustably connected with said stick and adapted to be swung from operative to inoperative position, and means 80 for locking the cymbal beater in operative or inoperative position.

4. A device of the class described comprising a base, a hollow post rising from said base, a pivoted jaw on the post and cooperative with the said base for clamping engagement with the hoop of a drum, a fork formed on said post, a rocking member pivoted in said fork, a beater stick adjustably connected in said member and having a resilient striker head, a foot pedal pivotally connected with said base, connection between the pedal and said member, resilient means fixed in said post and connected with the said member for tensioning the same, a cymbal beater adjustably connected with said stick and adapted to be swung from operative to inoperative position, means for locking the cymbal beater in operative or inoperative position, and means for limiting 100 the swinging movement of the beater in one direction.

In testimony whereof I affix my signature in presence of two witnesses.

FLOYD L. FRASER.
